Attn:

UNITED STATES PATENT OFFICE.

GEORGE WAINWRIGHT, OF BOSTON, MASSACHUSETTS.

BAG-FILLING MACHINE.

Application filed January 15, 1923. Serial No. 612,598.

To all whom it may concern:

Be it known that I, GEORGE WAINWRIGHT, a citizen of the United States of America, and resident of Boston, in the county of 5 Suffolk and State of Massachusetts, have invented new and useful Improvements in Bag-Filling Machines, of which the following is a specification.

This invention relates to bag filling machines and more particularly to machines for handling flat bags or envelopes into which a measured charge is fed whereupon the bags are closed and sealed, the entire operation being automatic.

10 Objects of the invention are to provide a machine of this character which will operate with speed and precision, which will not destroy a bag or become clogged and inoperative if any operation of the machine is missed, to provide for the feeding of more than one measured charge to the same bag, and in general to simplify and to improve prior devices in the interests of more efficient and satisfactory service.

15 The invention comprises a movable support or carrier which preferably takes the form of a rotatable table or disk upon which the bags are disposed and held in face or flat engagement. The carrier is stepped 20 around in one direction and means are provided in spaced relation for placing empty bags upon the support and for ejecting filled bags therefrom, and other means acting on the bags during their cycle of movement on the carrier to open, fill, close and seal the bags.

The carrier table or disk preferably rotates in a substantial vertical plane and the bags are placed thereon in inverted position 25 with their open ends disposed outwardly of the carrier. Suitable means grip each bag at a point remote from its open end to retain it upon the carrier. These grippers are moved to inoperative position by the bag 30 placing and ejecting means which may be arranged to advance from the rear of the carrier table or disk, suitable openings being provided in the carrier for this purpose. The bag placing means may take the form 35 of a suction head having the ejector member fast thereon so that the ejection of a filled bag occurs concomitantly with the placing of an empty bag, the ejection being operative on forward movement through one 40 opening in the carrier while the suction head

on return or reverse movement forcibly removes an empty bag from a bag magazine adjacent the carrier and disposes it flat against the carrier over the adjacent opening, a gripper seizing and retaining the bag 45 in place.

The invention further comprises a funnel mounted on the carrier for sliding movement into the open end of the bag to facilitate the filling thereof, means being provided for causing the mouth of the bag to open as the funnel moves forward and holding the flap of the bag out of the path of movement of the funnel. The entire 50 charge of the bag may be deposited in the 55 funnel at one station in the movement of the carrier or in installments at a plurality of stations. The invention further comprises novel means for gumming the bag flap after the withdrawal of the funnel and for folding the flap to seal the bag.

For the purpose of illustrating the invention one concrete embodiment thereof is shown in the accompanying drawings, in which:-

Fig. 1 is a front elevational view;

Fig. 2 is a side elevational view partly in section;

Fig. 3 is a detail elevational view of the Geneva movement for stepping around the 60 bag carrier;

Fig. 4 is an enlarged detail sectional view on the line 4—4 of Fig. 1;

Fig. 5 is a sectional view on the line 5—5 of Fig. 4;

Fig. 6 is an enlarged fragmentary plan view of one of the bag grippers on the carrier;

Fig. 7 is a sectional view on the line 7—7 of Fig. 1;

Fig. 8 is a sectional view on the line 8—8 of Fig. 1;

Fig. 9 is a sectional view on the line 9—9 of Fig. 1;

Fig. 10 is a sectional view on the line 10—10 of Fig. 1;

Fig. 11 is a sectional view on the line 11—11 of Fig. 10;

Fig. 12 is a sectional view on the line 12—12 of Fig. 1;

Fig. 13 is a sectional view on the line 13—13 of Fig. 1;

Fig. 14 is a sectional view on the line 14—14 of Fig. 13;

Figs. 15 and 16 are respectively front and 110

side elevational views of the combined suction head and ejector;

Fig. 17 is a plan view partly in section of the bag magazine;

Fig. 18 is a sectional view on the line 18—18 of Figs. 2 and 17; and

Fig. 19 is a sectional view on the line 19—19 of Fig. 2.

The embodiment of the invention chosen for the purpose of illustration comprises a machine for filling flat bags or envelopes with measured amounts of granular material such as seed. The processes of filling, closing and sealing bags are effected while the latter are supported in flat or face engagement with a bag supporter or carrier in the form of a disk or table 20 having a flat or plane front face and reinforcing ribs 21 at the rear, Figs. 4 and 5. This carrier is mounted for intermittent rotating movement in a substantially vertical plane and is arranged to support a plurality of flat bags X. In the embodiment shown, disk 20 has places for supporting twelve bags and in its rotated movement it stops successively at twelve stations A, B, C, D, E, F, G, H, I, J, K, L, (Fig. 1). The bags are placed upon the carrier at station A and ejected at station L by combined placing and ejecting means later to be described.

Disk 20 has a plurality of openings 22, of any desired form, rectangular in the present embodiment, with an extension 23 toward the axis of the carrier. The empty bags X are applied to the carrier at station A in inverted position by a suction head 24 advancing through opening 22, are securely retained on the carrier 20 by grippers 25 (Fig. 6) pivoted at 26 to brackets 27 adjustably secured to the face of the carrier by screws 28 extending through slots 29 in brackets 27. Each of the grippers 25 is adapted by means of a stiff spring 30 to press and hold the bottom of the bag against carrier 20 and each gripper has an abutment block 31 disposed within extension 23 of recess 22 to be contacted by means on suction head 24 such as arm 32 or by arm 33 on ejector 34 whereby the grippers are moved to inoperative position.

Secured to the carrier 20 are radially disposed plates or extensions 35 adjacent to and in alignment with openings 22, these extensions carrying spaced, radially disposed, undercut guide plates 36, Fig. 5, between which are mounted for sliding movement plates 37 having rounded lower ends 38 (station D, Fig. 1) and carrying arcuate plates 39 forming funnels having enlarged outer ends 40 and beveled and reduced inner ends 41, Fig. 4. To produce sliding movement of funnels 39, plates 37 extend beyond extensions 35 and carry rol-

lers 42 fitting in a cam groove 43 in an endless cam plate 44 surrounding carrier 20. Inward movement of funnels 39 occurs intermediate stations A and B to dispose the funnel within the open end of the bag as clearly indicated at stations C, F and G, Fig. 1, the extent of the entrance of the funnel being indicated at station D where the bag is omitted and at station E where the bag is partly cut away. After the bag is filled as at station F the funnel is withdrawn, withdrawal taking place in the embodiment shown intermediate stations G and H to permit the bags thereafter to be closed and sealed.

Assuming a bag upon the carrier 20 at station A, Fig. 1, movement of the carrier one step to station B, brings the bag X beneath a roller 45 resiliently supported by a spring arm 46, (Figs. 1, 10 and 11) in position to contact the bag approximately midway of its length to press the bag slightly into the opening 22 therebeneath in a manner to cause the mouth of the bag to open, the flap X' being meanwhile held down by a pad 47 resiliently carried by a flat spring 48, (Figs. 1, 10 and 12). As the funnel 39 moves inward by reason of the bend in the cam plate 44, the rounded end 38 of the plate carrying funnel 39 slips over the flap X' of the bag and into the open mouth of the bag, pad 47 being raised by the beveled end 41 of the advancing funnel. The length of pad 47 as shown in Fig. 12 is such that the pad slips from one funnel when the next succeeding bag is beneath the bag opener or roller 45. Thus funnels 39 serve as means for producing intermittent movement of pad 47 from its operative position.

During the next few stations such as C, D and E, in the embodiment shown, funnel 39 remains within the open end of the bag. At stations F and G charges of material may be deposited within the funnel to fill the bag. The charge may be deposited at one of the stations or at a plurality of stations as desired. However, to avoid duplication of parts, but one measuring device is shown which comprises a hopper 49 beneath which a drum 50 is rotated in timed relation with carrier 20, the drum having a plurality of measuring chambers 51 (in this instance six in number) having adjustable bottoms 52 to permit the charge to be varied. Drum 50 is arranged to rotate at twice the speed of carrier 20 and is timed to deposit a charge from one of the measuring drums 51 into a spout 53 which in turn delivers the charge into the enlarged end 40 of the funnels 39. The enlarged ends of the funnels 39 not only prevent the material from being spilled but also speed up the operation of the machine by being of sufficient capacity to hold the charges which

can pass into the bag while the carrier is in motion.

Between station G and H the funnels 39 are withdrawn from the bag which is now 5 filled and at station H adhesive such as mucilage or glue is applied to the tab X' by a pad 54 carried by a lever arm 55 and arranged for recurrent movement toward and from carrier 20. Pad 54 is supplied 10 with adhesive material by contact during its movement toward the carrier with a roller 56 mounted on a frame 57 reciprocable on guide rods 58 by the provision of a piston rod 58^a carrying a piston 59 in a 15 cylinder 60, the piston being normally retained in the upper end of the cylinder by spring 61. Any suitable means may be utilized for causing piston 59 to descend against spring 61 at the proper time such 20 as suction produced by an exhaust pump, not shown, connected to the cylinder by pipe 62. As the roller 57 descends between guides 58 it brushes against roller 63 partly within a glue box 64 which in turn is supplied 25 with glue by a constantly rotating roller 65 at least partially immersed in glue. The timing of these parts is such that as roller 56 reaches the limit of its downward movement or begins its upward 30 movement pad 54 wipes against it and transfers the adhesive thus received to the flap X' of the bag, the bag being held flat against carrier 20 by flat spring member or presser 66 (Fig. 7).

As pad 54 is withdrawn carrier 20 is stepped around moving the bag from station H to station I. At the beginning of this movement the flap X' of the bag is raised by a plow piece 67 which is supported by member 68 attached to the frame of the glue supplying mechanism, (Figs. 13 and 14) presser 66 still continuing to retain the body of the bag flat against the carrier. Plow 67 guides the flap of the bag 45 in front of a hinged plate 69 pivoted at 70 to a strap iron frame 71, plate 69 being normally retained in upright position, indicated in dotted outline, by the provision of a spring 72. An arm 73 secured to frame 50 71 carries a presser or retaining member 74 which takes the place of presser 66 and is arranged to engage the bag beyond the point covered by the flap when folded over. When the bag reaches station I hinge 55 plate 69 is actuated by means of a flexible connection 75 attached to an arm 76 (Fig. 1) to move the plate to the position shown in Fig. 8 to press the flap over against the bag to close the latter. Pressure upon the 60 sealed flap of the bag is continued during the next two stations J and K, by a brush 77 suitably supported by resilient strips 78 secured to members 79 which are attached to the cam plate 44. By maintaining pres-

sure upon the flap during at least two stations the glue or other adhesive has a chance to set so that the bag is properly sealed when ejected at station L.

The combined suction head and ejecting device which operates concomitantly at 70 stations A and L is disclosed in Figs. 15 and 16 and comprises a hollow lever 80 pivoted at 81 to the frame or base M of the machine, hollow lever 80 serving as means for connecting the suction head 24 to a source 75 of negative pressure later described. Secured to the upper portion of lever 80 in any suitable manner as by a collar 82 is an angularly disposed member or arm 83 having integral portions forming the ejector 34 80 and the gripper actuator 33. As indicated in Fig. 16 gripper actuator 33 contacts bag gripper 25 to move the latter to inoperative position before ejector 34 strikes the filled bag to force it beyond its funnel 39 85 therebelow and into a suitable box or container, not shown. Thus on advancing movement of the combined ejector and suction head a filled bag is ejected at station L and on reverse movement suction head 24 90 forcibly withdraws an empty bag from a bag magazine or holder 87 at station A and deposits the bag in face engagement with carrier 20, gripper actuator 32 permitting the gripper to move to operative position in time to clamp the bottom of the bag 95 against the carrier at the moment the suction is broken in head 24.

As illustrated in Fig. 2 the bag magazine 87 is supported on the base or frame M of 100 the machine by angular brackets 84 and by a vertical bracket 85 resting upon a horizontal brace 86. As indicated in Figs. 17 and 18 the magazine is substantially rectangular in form, the open end thereof of adjacent suction 105 head 24 being partly closed by retaining flanges or cleats 88. The manner in which the suction head 24 flexes the bag to withdraw it from between retainers 88 is indicated by broken lines in Fig. 17. Similar retainers or cleats 89 are provided upon the top of the magazine terminating in spaced relation to the front end 90 to permit the insertion of the bags which are continually urged toward the open end of the magazine by the provision of a follower 91 in the form of a plate having ears 92 extending through longitudinal slots 93 in the sides of the magazine, gravity means such as a weight 94 (Figs. 1 and 2) connected to ears 92 of the 120 follower by flexible members such as the ropes 95 passing over pulleys 96 being utilized for this purpose.

The mechanism for operating the various parts of the device in timed relation will 125 now be described, reference being had to Figs. 2 and 3. The shaft 99 of the carrier 20 is journaled in a bearing 100 in the upper

portion of the frame M and carries on its rear end the star wheel 101 of a Geneva movement, the pin wheel 102 of which is mounted upon a drive shaft 103 journaled 5 in bearings 104 on frame M. Star wheel 101 has pin grooves 105 corresponding in number to the twelve stations at which the carrier 20 stops during its cycle of movement, the carrier being rotated one step on each complete revolution of the main shaft 103. Any suitable means such as a belt (not shown) on pulley 103^a may serve to drive main shaft 103. Drum 50 of the measuring device is driven from the shaft 99 of the 10 carrier by means of chain and sprocket connection 106, the number of teeth on the sprockets being such as to produce a two-to-one driving ratio. Roller 65 emersed in the glue box 64 may be driven from the main shaft 103 by a chain and sprocket connection 107 to a counter shaft 108 which drives the shaft of the roller through beveled gears 109, Fig. 1. The movement of the combined ejector and suction head 24, 34, of 15 the glue applying pad 54 and of the flap folder 69 is controlled by a cam 110 on the main shaft acting on a slide 111 (Figs. 2 and 19) on base M through a roller 112 on the post 113, the roller being maintained in 20 contact with the face of cam 110 by the provision of a coil spring 114 secured in any suitable manner to the base and to a hook 115 on slide 111. The connections from slide 111 to the above mentioned elements 25 controlled thereby comprise a lever 116 pivoted to a post 117, within the base of the machine, the short arm of the lever being connected to a rod 118 on slide 111. The long arm of lever 116 is connected to hollow 30 lever 80 carrying the suction head 24 and the ejector 34 by a link 119, the connection of the link to lever 80 being by means of a clamping collar 120 adjustment of which longitudinally of lever 80 will vary the 35 throw of the suction head and ejector. From lever 80 extends an ear 121 to which is pivoted a link 122 the other end of which is pivoted to the short arm of lever 55 which carries the glue applying pad 54. Lever 40 55 is pivoted at 123 to one side of the bag magazine 87 and has an arm 124 projecting toward carrier 20 to which is secured the flexible member or rope 75 by which the flap folder 69 is actuated. Thus when roller 112 45 of slide 111 rides up upon the projection of cam 110, the lower arm of lever 80 is drawn to the left, (Fig. 3) throwing suction head 24 and ejector 34 forward and at the same time swinging the long arm of 50 lever 55 inwardly to force glue pad 54 against the flap of the bag at station H and pulling downwardly upon connection 75 to cause flap folder 69 to seal a bag at station I. As roller 112 rides down from the crest 55 of cam 110 lever 55 swings outwardly away

from the carrier, flap holder 69 returns to normal position and suction head 24 is drawn back to apply a bag to the carrier at station A. For producing suction in head 24 at the proper instant an exhaust pump 126 70 is provided actuated by a crank 127 on main shaft 103 through a link 128 attached to piston rod 129, the connections from the pump to the suction head 24 comprising pipe 130 and a flexible connection 131, such 75 as a piece of rubber hose pipe, interposed between pipe 130 and the lower end of hollow lever 80.

The operation of the machine as a whole will be apparent from the earlier functional 80 description and the later description of the mechanical connections by which the elements perform their respective functions. The flat bags are disposed with their flap sides in face engagement with the carrier 85 table or disk 20 and the operations of opening, filling, gluing and sealing the bag are effected while the bags are so supported. Inasmuch as none of the elements operative 90 to fill and close the bag actually grip the latter it will be apparent that failure of any of the operative steps in treating the bag will not destroy the bag nor prevent the operation of the machine through clogging or otherwise interfering with any portion 95 of its mechanism.

I claim:

1. In a machine of the character described, a movable carrier disk, means retaining bags in face engagement with said disk, and 100 means for opening and filling the bag while supported on said disk.
2. In a machine of the character described, a movable carrier disk, means retaining bags in face engagement with said disk, and 105 means for opening, filling and closing the bag while supported on said disk.
3. In a machine of the character described, a movable carrier disk, means retaining bags in face engagement with said disk, and 110 means for filling, gumming and sealing the bag while supported on said disk.
4. In a machine of the character described, a movable bag carrier disk, means retaining bags flat against one face of said disk, means 115 advancing said carrier from a bag receiving station to a bag ejecting station, and means for opening, filling and closing the bags while supported on said carrier in transit from one station to the other. 120
5. In a machine of the character described, a movable bag carrier disk, means retaining bags upon one face of said disk, means for intermittently advancing said carrier from a bag receiving station to a bag 125 ejecting station, and means for opening, filling, gumming and sealing the bags while supported on said carrier in transit from one station to the other.
6. In a machine of the character described, 130

- a carrier disk, means for advancing a bag into face engagement with said disk, and means for gripping and holding the bag on the disk.
5. In a machine of the character described, a carrier disk, means for advancing a bag into face engagement with said disk, and means for gripping the bottom of the bag to hold it upon the disk.
10. In a bag filling machine a carrier disk having an opening therein, means disposing a bag in face engagement with said disk over said opening, and means for retaining the bag in face engagement with the disk.
15. In a bag filling machine, a movable carrier disk having an opening therein, means arranged to be advanced through said opening to dispose a flat bag in face engagement with said disk, and means for gripping and holding the bag on said disk.
20. In a bag filling machine, a movable carrier disk having an opening therein, a bag holder adjacent said disk, and means arranged to be intermittently advanced through said openings in succession to seize a bag from said holder and deposit it in face engagement with said disk.
25. In a bag filling machine, a movable carrier disk having an opening therein, a bag holder adjacent said disk, a suction head arranged to be intermittently advanced through said openings to seize a bag from said holder and deposit it in face engagement with said disk, and means yieldingly retaining this bag upon the disk.
30. In a bag filling machine, a movable carrier disk having an opening therein, a bag holder adjacent said disk, a suction head arranged to be intermittently advanced through said openings to seize a bag from said holder and deposit it in face engagement with said disk, and means yieldingly retaining the bag upon the disk, said means being moved to inoperative position on movement of said head in one direction and restored to operative position to hold the bag on reverse movement of said head.
35. In a machine of the character described, a movable carrier disk having an opening therein, a member arranged to be advanced through said opening to dispose a bag in inverted position flat against said disk over said opening, and a gripper arranged to engage the bag to hold in place upon the disk.
40. In a machine of the character described, a movable carrier disk having an opening therein, a member arranged to be advanced through said opening to dispose a bag in inverted position flat against said disk over said opening, and a spring pressed gripper adjustably mounted on said disk for retaining the bag in place upon the disk.
45. In a machine of the character described, a movable carrier disk having an opening therein, a member arranged to be advanced through said opening to dispose a bag in inverted position flat against said disk over said opening, and a spring pressed gripper for retaining the bag in place upon the disk, and an extension on said member arranged to open said gripper when said member is advanced.
50. In a bag filling machine a movable carrier disk having a plurality of bag gripping members thereon, means for recurrently disposing a bag in face engagement with said disk in position to be gripped by one of said members.
55. In a bag filling machine a movable carrier adapted to be intermittently advanced, a plurality of bag gripping members thereon in spaced relation, and means operative during the periods of rest of said carrier for disposing a bag flat against said carrier in position to be gripped by one of said members.
60. In a bag filling machine a circular carrier disk arranged to be intermittently stepped around in one direction, a plurality of bag gripping members thereon, and means for concomitantly disposing an empty bag in position to be gripped by one of said members and for ejecting a filled bag from beneath another of said members.
65. In a bag filling machine a circular carrier disk having a plurality of openings therein, a spring pressed gripper member adjacent each of said openings, and means recurrently advanced through the openings for moving at least one of said members to inoperative position.
70. In a bag filling machine a circular carrier disk having a plurality of openings therein, a spring pressed gripper member adjacent each opening for holding a bag flat against said disk, and means recurrently advanced through adjacent ones of said openings to move the corresponding gripper members to inoperative position.
75. In a bag filling machine a circular carrier disk having a plurality of openings therein, a spring pressed gripper member adjacent each opening for holding a bag flat against said disk, and means recurrently advanced through adjacent ones of said openings to move the corresponding gripper members to inoperative position, said means including an ejector for removing a filled bag from over one opening and a suction head for disposing an empty bag over the adjacent opening in position to be gripped by its corresponding member.
80. In a bag filling machine, a bag carrier upon which bags are adapted to be mounted in face engagement therewith, and a funnel mounted on said carrier for radial movement into the open end of a bag.

23. In a bag filling machine, a bag carrier upon which bags are adapted to be mounted in face engagement therewith, and a plurality of funnels slidably mounted on said carrier for movement into and out of the bags.
24. In a bag filling machine, a circular carrier disk, a funnel slidably mounted on said disk, and cam means for moving said funnel relative to said disk.
25. In a bag filling machine, a circular carrier disk, adapted to be stepped around in one direction, a funnel mounted for radial movement on said disk, and means including a cam track for moving said funnel during rotation of said disk.
26. In a bag filling machine, a circular carrier disk, adapted to be stepped around in one direction, means supported on said disk for opening the mouth of a bag, and a funnel on said disk arranged for movement into the open mouth of the bag to facilitate filling the same.
27. In a bag filling machine, a circular carrier disk, adapted to be stepped around in one direction, means supported on said disk for opening the mouth of a bag, a funnel on said disk arranged for movement into the open mouth of the bag, and means for holding the flap of the bag out of the path of movement of said funnel.
28. In a bag filling machine, a carrier having an opening therein, means retaining a bag in face engagement with said carrier above said opening, and means engaging the bag to force it within said opening thereby to open the mouth of the bag for the insertion of a filling spout.
29. In a bag filling machine, a carrier disk having an opening, means retaining a bag upon said disk above said opening, and a roller arranged to force the bag within said opening sufficiently to open the mouth of the bag.
30. In a bag filling machine, a bag carrier, means for supporting an empty bag in face engagement with said carrier, a funnel slidably mounted on said carrier adjacent the bag, means for opening the mouth of the bag, and means for concomitantly advancing said funnel into the open mouth of the bag.
31. In a bag filling machine, a bag carrier, means for supporting an empty bag in face engagement with said carrier, a funnel slidably mounted on said carrier adjacent the bag, means for opening the mouth of the bag, means for concomitantly advancing said funnel into the open mouth of the bag, and means for holding the flap of the bag out of the path of movement of said funnel.
32. In a bag filling machine, a bag carrier, means for supporting an empty bag in face engagement with said carrier, a funnel slidably mounted on said carrier adjacent the bag, means for opening the mouth of the bag,
- bag, means for concomitantly advancing said funnel into the open mouth of the bag, and a holder for retaining the flap of the bag down during the initial movement of said funnel, said holder being moved to inoperative position during the subsequent movement of said funnel.
33. In a bag filling machine, a bag carrier, means for supporting an empty bag in face engagement with said carrier, means for opening the mouth of the bag, a funnel having a beveled end arranged for movement into the open end of the bag, and a resiliently mounted holder for retaining the flap of the bag down during the initial advance of said funnel, the beveled end of the funnel serving to move said holder to inoperative position.
34. In a bag filling machine, a movable support for a plurality of bags, means for holding the flaps of the bags in succession flat against said support to permit the insertion of a funnel within the open mouth of the bag, and means for recurrently moving said means to inoperative position during the movement of said support.
35. In a bag filling machine, a movable support for a plurality of bags, said support being adapted to be intermittently advanced, a flat holder adjacent the path of movement of said support, said holder being arranged to hold the flap of each successive bag flat against said support to permit the insertion of a funnel within the bag, and means for retaining said holder inoperative during the advance of said support.
36. In a bag filling machine, a movable support for a plurality of bags, said support being adapted to be intermittently advanced, a flap holder adjacent the path of movement of said support, said holder being arranged to hold the flap of each successive bag flat against said support to permit the insertion of a funnel within the bag, and means movable with said support for retaining said holder inoperative during the advance of said support.
37. In a bag filling machine, a movable support for a plurality of bags, said support being adapted to be intermittently advanced, a resiliently mounted flap holder adjacent the path of movement of said support to hold the flap of each successive bag flat against said support to permit the insertion of a funnel within the bag, and means for retaining said holder inoperative during the advance of said support.
38. In a bag filling machine, a movable support for a plurality of bags, said support being adapted to be intermittently advanced, means for feeding empty bags to a position adjacent said support, and means for forcibly withdrawing a bag from said feeding means and disposing it flat against said support.

39. In a bag filling machine, a movable support for a plurality of bags, said support being adapted to be intermittently advanced, means for feeding empty bags in inverted position into proximity to the path of movement of said support and means for forcibly withdrawing a bag from said feeding means and disposing it flat against said support.
40. In a bag filling machine, a movable support for a plurality of bags, said support being adapted to be intermittently advanced, a holder for empty bags having its open end disposed adjacent said support, gravity actuated means continually urging the bags toward said open end, and means for forcibly withdrawing the foremost bag from said holder and disposing it flat against said support.
41. In a bag filling machine, a movable support for a plurality of bags, said support being adapted to be intermittently advanced, a holder for empty bags having its open end disposed adjacent said support, gravity actuated means continually urging the bags toward said open end, and suction means operative during the periods of rest of said support for withdrawing a bag from said holder and depositing it upon said support.
42. In a bag filling machine, a movable support for a plurality of bags, said support being adapted to be intermittently advanced, a holder for empty bags having its open end disposed adjacent said support, gravity actuated means continually urging the bags toward said open end, and a suction head recurrently advanced during the periods of rest of said support forcibly to withdraw a bag from said holder and to dispose it flat against said support.
43. In a bag filling machine, a movable support for a plurality of bags, said support being adapted to be intermittently advanced, a holder for empty bags having its open end disposed adjacent said support, gravity actuated means continually urging the bags toward said open end, retainers adjacent the open end of said holder to prevent the bags from being forced out by said means, and a suction head recurrently advanced to forcibly withdraw a bag from said holder and deposit it upon said support.
44. In a bag filling machine, a support having a plane surface and means for retaining a plurality of bags in face engagement with said surface, means for intermittently advancing said support in one direction, and means for concomitantly removing a filled bag from said support and placing an empty bag on said support.
45. In a bag machine a circular bag support having a plurality of openings therein, means adjacent each opening for retaining a bag thereover, and means simultaneously advanced through two of said openings to remove one bag from said support and to position another bag on said support.
46. In a bag machine a circular bag support having a plurality of openings therein, means adjacent each opening for retaining a bag thereover, and a combined ejector and carrier arranged to be recurrently advanced through adjacent ones of said openings concomitantly to remove a bag from said support and to position a bag upon said support.
47. In a bag machine a circular bag support having a plurality of openings therein, means adjacent each opening for retaining a bag thereover, and a combined ejector and suction head arranged to be recurrently advanced through adjacent ones of said openings to eject a bag on advancing movement and to position a bag on said support on reverse movement.
48. In a bag filling machine, a carrier disk, means for retaining a plurality of flat bags with their flap sides flat against said disk, means intermittently advanced to apply adhesive to the flaps of successive bags, and means for folding the flaps and holding them against the bags until the adhesive has set.
49. In a bag filling machine, a carrier disk, means for retaining a plurality of flat bags with their flap sides flat against said disk, means intermittently advanced to apply adhesive to the flaps of successive bags, means operated in timed relation with said first means to supply the latter with adhesive and means for folding the flaps and holding them against the bags until the adhesive has set.
50. In a bag filling machine, a carrier disk, means for retaining a plurality of flat bags with their flap sides flat against said disk, a member intermittently advanced to apply adhesive to the flaps of successive bags, reciprocable means operated in timed relation with said member for supplying the latter with adhesive, and means for folding the flaps on the bags to seal the latter.
51. In a bag filling machine, a carrier disk adapted to be stepped around in one direction, means for retaining a plurality of flat bags with their flap sides flat against said disk, means intermittently advanced to apply adhesive to the flaps of the bags in succession, a stationary plow member for lifting the flaps as said disk is rotated, and intermittently operated means for folding and pressing the flaps upon their respective bags to seal the same.
52. In a filling machine for flat bags, a carrier disk mounted for movement in a vertical plane, means on said disk for retaining bags in face engagement therewith, and means operable during a single cycle of

movement of said disk for filling, gumming and sealing said bags.

53. In a filling machine for flat bags, a carrier disk mounted in a vertical plane, means on said disk for retaining bags in face engagement therewith, means for intermittently stepping said disk around whereby said disk is stopped at a plurality

of stations during a single cycle of movement, and means at and intermediate certain of said stations for filling, gumming and sealing said bags. 10

Signed by me at Boston, Massachusetts, this 30th day of December, 1922.

GEORGE WAINWRIGHT.
